[57] **ABSTRACT**

Apparatus for bagging slugs of cookies in side-by-side relation, in preselected groups including a slug conveyor for supplying slugs of cookies from a sandwiching and counting apparatus to a series of bagging or wrapping stations, so arranged as to accommodate the selection of any desired number of stations, and to supply the cookies in a continuous supply to the preselected stations in groups of two, three or four side-by-side groups of cookies, with the number of cookies in each slug preselected by the operator of the machine.

APPARATUS FOR SUPPLYING SLUGS OF COOKIES IN PRESELECTED SIDE-BY-SIDE GROUPS FOR BAGGING

FIELD OF THE INVENTION

This invention relates generally to apparatus for segregating and supplying slugs of cookies to a preselected number of bagging stations for bagging, in which the number of cookies in each slug and number of slugs delivered for bagging is at the selection of the operator of the machine.

PRIOR ART

This invention is an extension of the developments of the tray loader of U.S. Pat. No. 3,290,859, dated Dec. 13, 1966 and the Richard C. Talbot application for patent for "Converger and Feeder for Cookies for Wrapping", Ser. No. 74,418, filed Sept. 22, 1970, now U.S. Pat. No. 3,627,102 which patent and application are assigned to the assignee of the present invention.

SUMMARY, ADVANTAGES AND OBJECTS OF THE INVENTION

Cookies are transferred from the sandwich machine and grouped in slugs of a preselected number of cookies in each slug, and delivered to a transfer conveyor transferring a plurality of slugs in side-by-side relation along drop gates disposed over a drop chute, converging the cookies for delivery to a slug conveyor, and depositing a slug of cookies between each pair of flights of the slug conveyor in a continuous operation. The transfer conveyor is driven in dwells and the drop gates of the slug conveyor open during each dwell and deposit the cookies into a drop chute which converges the groups of slugs and drops the slugs between the flights of the slug conveyor. The slug conveyor carries the slugs of cookies for deposit into from one to six bagging stations and delivers the cookies to the selected bagging stations through drop chutes, operable to drop the cookies into side-by-side troughs corresponding to the number of slugs delivered. A slug pusher operating in timed relation with respect to the dropping of cookies to the bagging station drop chute, pushes the cookies along converging troughs fitting into the mouths of bags extending along the troughs. The completion of pushing the cookies into the bag may be a manual operation, after which the bags may be heat-sealed by a machine separate from the bagging machine. The drop gates of the slug conveyor open to deliver the slugs to the bagging stations in staggered relation with respect to each other, to balance the load on the machine. As for example, where six bagging stations are in use, the slugs may be dropped into stations four, five, two, six, three and one or in any other preselected order.

The bagging stations are spaced along opposite sides of the slug conveyor and separate jack shafts are provided for the bagging stations at each side of the machine. Change speed gearing is provided in the drive to the jack shafts to drive the jack shafts at speeds corresponding to the groups of slugs to be bagged, and independent phase selector drives are provided between the jack shafts and the bagging stations, and drive individual cams and cranks at each station controlling dropping of the slugs of cookies from the slug conveyor,

dropping the slugs of cookies from the drop chute into the bagging trough and the operation of pushing the cookies along the bagging trough into the bag. The timing of the dropping of cookies from the slug conveyor, the dropping of the cookies from the drop chute to the delivery trough, and the pushing of the cookies may be varied at each bagging station through the positioning of the cams by the phase selector drives in accordance with the number of groups of slugs to be bagged and the selected number of stations to be operated, to assure the continuous dropping of the cookies from the slug conveyor to the preselected bagging stations with no piling up or spilling of cookies, or gaps or interruptions in filling of the slug conveyor and the bagging of cookies at the preselected bagging stations.

An advantage of the present invention is that articles, such as cookies may be bagged in a more efficient and expeditious manner than formerly in any number of series of bagging stations, delivering the articles for bagging in a preselected order.

Another advantage of the invention is that the drive to the slug conveyor, the drop gates for the slug conveyor and the drop gates dropping cookies to the bagging station are fixed to operate in timed relation with respect to each other, so the release of slugs from the slug conveyor will be at the proper timed intervals to fill the drop chutes and troughs at the bagging stations in a continuous operation during the entire bagging operation.

A further advantage of the invention is that individual controls controlling the dropping of slugs from the slug conveyor, the dropping of slugs from the drop chute into the bagging troughs and the pushing of cookies along the chutes into the bags at each bagging station are so operated as to enable the disconnection or connection of any bagging station at the selection of the operator of the machine.

Still another advantage of the invention is the provision of a phase selector drive mechanism at each bagging station, driven in accordance with the speed of travel of the slug conveyor, attaining the release of slugs from the slug conveyor and drop chutes to the bagging station at the proper timed intervals, which phase selector drive may vary the phases of the operating parts of the apparatus in accordance with the number of articles to be loaded, the number of stations in use and the speed of travel of the slug conveyor to keep the dropping and pushing operations in phase with travel of the slug conveyor in a simple operation by the operator of the machine.

A principal object of the invention, therefore, is to provide an improved form of apparatus for bagging articles, such as cookies at a plurality of bagging stations, at any one of a number of preselected stations in a simple and expeditious manner, assuring no interruption in the bagging or packaging of the articles.

Other objects, features and advantages of the invention will be readily apparent from the following description of certain preferred embodiments thereof, taken in conjunction with the accompanying drawings, although variations and modifications may be effected without departing from the spirit and scope of the novel concepts of the disclosure.

DESCRIPTION OF THE DRAWINGS

FIG. 1 is a diagrammatic plan view of a cookie bagging apparatus constructed in accordance with the principles of the present invention.

FIG. 2 is a diagrammatic view in side elevation of the bagging apparatus shown in FIG. 1.

FIG. 3 is a fragmentary perspective view looking at the transfer station and showing the transfer conveyor in position to transfer and deposit cookies between the flights of the slug conveyor.

FIG. 4 is a fragmentary transverse sectional view taken along the transfer station shown in FIG. 3 with certain parts removed in order to illustrate the drop chute converging the slugs of cookies dropped from the transfer conveyor, and transferring the cookies to the flights of the slug conveyor.

FIG. 5 is a fragmentary diagrammatic transverse sectional view taken through the apparatus at a bagging station, and showing the dropping of cookies from the slug conveyor to a drop chute at a bagging station with certain parts broken away and certain other parts shown in section.

FIG. 6 is a fragmentary sectional view showing in detail a drop chute, receiving slugs of cookies from the slug conveyor, at a bagging station for dropping the slugs to a bagging chute.

FIG. 7 is a diagrammatic fragmentary sectional view illustrating the slug conveyor drop chute and bagging chute at a bagging station, and generally showing the drive to the pusher pushing groups of cookies along the bagging chute for bagging.

FIG. 8 is a fragmentary perspective view with parts broken away in order to show the pusher and bagging chute at a bagging station.

FIG. 9 is a partial fragmentary transverse sectional view at a bagging station, looking at a bagging chute and pusher, at the receiving end of the chute.

FIG. 10 is a fragmentary perspective view looking toward the bagging trough at a bagging station and showing the pusher and converging troughs converging the cookies to the bagging trough to be pushed into a bag and inserted along the bagging trough.

FIG. 11 is a fragmentary transverse sectional view taken through the slug conveyor.

FIG. 12 is a partial fragmentary plan view of the slug conveyor.

FIG. 13 is a diagrammatic view of the slug conveyor showing the positions of the supporting gates for cookies in closed positions and in open positions with certain parts removed.

FIG. 14 is a fragmentary plan view with parts removed and other parts broken away and in section showing the adjustable guides for the sides of the slug conveyor, and the means for laterally adjusting the guides toward and from each other.

FIG. 15 is an enlarged detail top plan view illustrating the adjusting means for the side guide positioner for the side guides of the slug conveyor.

FIG. 16 is a fragmentary detail view in side elevation showing the actuating means for the side guide positioners.

FIG. 17 is a fragmentary view in side elevation with certain parts in section, and showing the toggle lock for locking the positioner and side guides for the slug conveyor in position.

FIG. 18 is a fragmentary transverse sectional view illustrating the change speed drive to the jack shafts for driving the dropping and pushing mechanism at the bagging stations at each side of the machine.

5 FIG. 19 is a view in transverse section, illustrating the differential mechanism driven from the jack shaft, for driving a cam shaft at a bagging station, controlling the dropping and discharge operation of the slugs of cookies.

10 FIG. 20 is a partial fragmentary longitudinal sectional view taken through the differential and showing the cams on the cam shaft and the crank for effecting operation of the dropping and pushing mechanism at a bagging station.

15 FIG. 21 is a fragmentary detail view illustrating the adjustment for means for adjusting the differential and the cams and crank shaft in accordance with the groups of slugs to be bagged.

20 FIG. 22 is a diagrammatic view diagrammatically showing the cam controlling the dropping of cookies from the drop chute to the bagging chute and controlling the dropping of cookies from the slug conveyor into the drop chute showing the mechanism for rendering a bagging station inoperative, in position to render a bagging station inoperative.

25 FIG. 23 is a diagrammatic view showing the cam and microswitch for controlling dropping of the cookies from the slug conveyor.

30 FIG. 24 is a diagrammatic view, diagrammatically showing a portion of a cam operating the drop gates at a bagging station showing the mechanism in an operative position; and

35 FIG. 25 is a diagrammatic view diagrammatically showing the drive connections to the transfer conveyor, slug conveyor, and differentials at each bagging station.

MACHINE IN GENERAL AND TRANSFER TO SLUG CONVEYOR

In FIG. 1 of the drawings, we have diagrammatically shown in plan, a conveyor 10 conveying cookies from a bake oven (not shown). The cookies are taken by hand from the conveyor 10 and transferred to side-by-side vibratory feeder troughs 11 on one side of the conveyor, and into the vibratory feeder troughs 12 on the opposite side of the conveyor 10, and fed to a sandwich machine 13 coating the cookies with cream and making the cookies into sandwiches in a manner similar to that shown and described in U.S. Pat. No. 2,936,557, so not herein shown or described further.

From the sandwich machine, the sandwiched cookies are transferred in rows, herein shown as being in four rows, to a counting conveyor 15, separating the rows of cookies into slugs of a preselected number and delivering the slugs in side-by-side relation to a transfer conveyor 16. The transfer conveyor 16 transfers the cookies along drop gates 17 (FIG. 4), which are movable to release the slugs of cookies to the space between the flights of a slug conveyor 19, in timed relation with respect to travel of the slug conveyor, to fill the space between each flight of the slug conveyor upon traveling movement thereof. The counting conveyor, transfer conveyor and drop gates are shown and described in U.S. Pat. No. 3,290,859, so need not herein be shown or described, except insofar as the transfer conveyor and drop gates cooperate to continuously fill the flights

of the slug conveyor as traveling from the discharge of the transfer conveyor, along and between a series of bagging stations one, three and five on one side of said slug conveyor and two, four and six on the opposite side of said slug conveyor.

The transfer conveyor 16 is driven from the mechanism driving the counting conveyor 15, in dwells and the cookies are discharged during each dwell. As shown in FIG. 25, the drive to said transfer conveyor includes a drive shaft 18 driven from a motor 24 through a phase variator 34 and a suitable drive train including change speed gearing 38. The change speed gearing synchronizes the speed of the shaft 18 of the counting conveyor leading from the sandwich machine to give the proper number of revolutions per slug, and the proper number of cookies going into a slug and coordinates the speed of travel of the transfer conveyor with the slug conveyor. The phase variator 34 synchronizes the timing of the drop from the transfer conveyor to the slug conveyor.

The transfer conveyor 16 has attachments 20 spaced therealong (FIGS. 3 and 4) and secured to the chains (not shown) of said conveyor and depending therefrom when the conveyor is traveling along its conveying run. Each attachment 20 has laterally spaced flights 21 extending downwardly therefrom between side rails 22, for conveying slugs or rows of cookies between said side rails 22 and along the drop gates 17. The drop gates 17 are movable laterally relative to the side rails 22 to drop the slugs of cookies into a drop chute 23, converging the slugs of cookies from their lateral spacing on the transfer conveyor to the spacing between the flights of the slug conveyor 19, and guiding the slugs of cookies in the space between the flights of the slug conveyor to rest on drop gates 25, forming the material carrying flights of the slug conveyor.

The drop gates 17 are part of the laterally movable drop gate carriage 26 (FIG. 4), which is suspended from rock shafts 27 on pairs of parallel links 28. The rock shafts 27 are journaled in aligned bearing supports 29 secured to the main frame of the machine. The parallel links 28 have shafts 30 mounted on their lower ends and mounted at their opposite ends in upright brackets 31 on the carriage 26. As in the aforementioned application Ser. No. 74,418, filed by Richard C. Talbot for "Converger and Feeder for Cookies for Wrapping".

The drop gate carriage 26 is moved back and forth in timed relation with respect to travel of the transfer conveyor 16 to drop four slugs or rows of counted cookies into the drop chute 23, by rocking movement of a lever arm 32, secured to and depending from a rock shaft 33. The lever arm 32 has a link 35 pivotally connected to its lower end, at one end of said link and pivotally connected to the link 28, at the opposite end of said link, for moving the drop gates 17 out of supporting relation with respect to slugs of cookies upon rocking movement of said rock shaft.

The mechanism for actuating the drop gates in timed relation with respect to intermittent travel of the transfer conveyor 16 and continuous travel of the slug conveyor 19 to drop the slugs of cookies to the drop gates 25 for continuously supplying each flight of the slug conveyor 19 with a slug of cookies is by operation of a cam (not shown) driven in timed relation with

respect to travel of the transfer conveyor 16 by the drive 18 through a suitable drive train, as shown and described in U.S. Pat. No. 3,290,859, so not herein shown or described in detail.

5 The chute 23 disposed beneath the transfer conveyor 16 has outer chutes 40 and inner chutes 41 disposed therebetween. The outer chutes 40 have parallel side walls 42 inclined to converge the slugs of cookies to the spacing between the flights of the slug conveyor. The inner chutes 41 have outer inclined side walls 43 extending parallel to the side walls 42 and inner side walls 44 midway between the side walls 43 and extending vertically. The side walls 42 converge the slugs of cookies inwardly toward each other, while the side walls 43 and 44 cooperate to converge the rows of cookies, and maintain the required spacing between the rows of cookies, as dropped in the spaces between the flights of the slug conveyor 19. As for example, the spacing between 10 the slugs of cookies when traveling along the drop gates 17 is in the order of 4 $\frac{1}{4}$ inches, while the spacing between the rows of cookies on the drop gates 25 of the slug conveyor is in the order of 3 inches.

Bagging Station Drop Chute

20 A drop chute 45 is provided at each bagging station in cookie receiving relation with respect to the slug conveyor 19 disposed thereabove (FIGS. 5 and 7). The drop chute 45 is herein shown as being provided with three pockets or chutes 46 although the number of chutes may be varied in accordance with the number of slugs to be dropped, the side walls of which converge from the upper ends toward the lower ends thereof, to receive slugs of cookies dropped from the slug conveyor 19, and momentarily hold the slugs of cookies for discharge onto a bagging chute 47 disposed therebeneath, and extending transversely of the path of travel of the slug conveyor 19, and parallel to the slugs of cookies thereon.

30 Drop gates 48 extend along the bottoms of the pockets 46 for supporting the rows of cookies as dropped into said pockets or chutes from the slug conveyor 19. The drop gates 48 are mounted on parallel spaced bars 50 having bearing bosses 51 extending upwardly of their outer ends forming supports for shafts 52. Parallel links 53 suspend the bars 50 and shafts 52 from parallel shafts 55 supported on the main frame of the machine and extending laterally thereof.

40 A crank arm 56 is secured to one shaft 53 and is rocked up and down, to move the drop gates 48 into and out of slug supporting positions by a link 57, pivotally connected to the outer end of said crank arm at its lower end and pivotally connected at its upper end to an actuating lever 59 pivotally mounted on a horizontal shaft 60 extending longitudinally of the main frame of the machine and on the opposite side of said main frame from the link 57. The opposite end of the actuating arm 59 from the shaft 60 is pivotally connected to the upper end of the link 57 on a pivot pin 61 (FIG. 7).

50 The actuating lever 59 is moved up and down in timed relation with respect to the speed of travel of the slug conveyor 19, the slugs of cookies to be delivered from said slug conveyor and the number of bagging stations in operation, by a cam disk 63 having a camming groove 64 in one face thereof and a follower roller 65

rotatably mounted on said actuating arm intermediate the ends thereof and extending within and having engagement with said cam groove 64. The mechanism for operating said cam in the proper timed relation with respect to the slugs of cookies to be delivered will hereinafter more clearly appear as this specification proceeds.

Bagging Chute And Usher

The bagging chute 47, shown in FIG. 5, includes a stationary base 66 inclined upwardly to the respective bagging station and having spaced angularly outwardly extending side walls 67 in the form of angles having horizontal legs welded or otherwise secured to said base. Side wall members 69 in the general form of equilateral triangles are disposed between the side walls 67 and the sides thereof are inclined to diverge from the side walls 67 to form three hopper-like troughs extending parallel to each other, for receiving the slugs of cookies dropped from the drop chute 45 by the drop gates 48. The side walls may converge to rounded bottoms, as shown in FIG. 10. The bagging chute 47 is shown in FIG. 7 as inclined upwardly relative to a rear pusher 73 movable in the plane of said bagging chute to move the cookies along said bagging chute to a converging bagging chute 71 converging the cookies to a chute 72 which may extend within a bag to be filled with side-by-side slugs of cookies.

A pusher 73 is provided to move the slugs of cookies along the bagging chute 47, converging chute 71 and chute 72 into a bag (FIG. 10). The pusher 73 is in the form of a transverse bar 74 inclined at the angle of the chute 47 and the base plate 66. The pusher 73 is mounted on a bar 75 extending at the angle of inclination of the base 66 on rollers 76 and 77 having rolling engagement with upper right angled faces of the bar 75 and rollers 79 and 80 engaging the downwardly facing right angled faces of the bar 75 (FIGS. 8 and 9).

There are two sets of rollers 76, 77 and 79, 80 which are spaced longitudinally with respect to each other along the respective downwardly and upwardly facing right angled faces of roller support bars 81 and 82. The supports bars 81 and 82 are mounted intermediate their ends on suitable brackets 83 and 84 mounted on the vertically extending leg 85 of an angle bracket mounted on the underside of the plate 74 adjacent one end thereof in a suitable manner. Bolts and nuts 86 extend through slots 87, to accommodate adjustment of the bars 81 and 82 with respect to each other, to provide a free rolling support for the pusher 73 along the bar 75.

A pivot pin 88 extends laterally of the vertical leg of the angle bracket 83 and forms the pivotal mounting for a link 89 pivoted at its opposite end to the lower end portion of a bell crank 90 on a pivot pin 91. The bell crank 90 is pivoted intermediate its ends on a bracket 93 extending inwardly of a vertical frame member 94 of the main frame for the machine on a pivot pin 95. A lever arm 96 extends vertically of the pivot pin 95 along the outside of the vertical frame member 94 and is pivotally connected at its lower end to a link 97 as by a pivot pin 99. The link 97 extends upwardly along the outside of the frame member 94 and is pivotally connected at its upper end to the outer end of a slug pusher lever 100 as by a pivot pin 101. The slug pusher lever

100 is freely pivoted at its end opposite link 97, on the pivot shaft 60, which also forms a pivotal mounting for the drop gate actuating lever 59.

The operative connection to the slug pusher lever 100 for pivoting said lever up and down about the axis of the pivot shaft 60 comprises a crank 103 on a cam shaft 104. Said cam shaft 104 forms a drive shaft for the cam disk 63 and crank 103, in a manner which will hereinafter more clearly appear as this specification proceeds. A link 106 is pivotally connected to the crank 103 at one end on a pivot pin 107 and at its lower end to the slug pusher lever 100, intermediate the ends of said lever on a pivot pin 109, to move said slug pusher 73 along the support and guide bar 75 in upward supply and downward return directions, in an obvious manner.

The transverse bar 74 of the pusher 73 forms a mounting for a pusher plate 110 extending perpendicular to said bar 74 and depending therefrom. The pusher plate 110 depends from a right angled mounting plate 111 mounted on top of the transverse bar 74 as by nuts and bolts, to position the pusher plate 110 in advance of said transverse bar 74.

20 The pusher plate 110 has a series of pusher members extending within the troughs formed by the walls 67 and 69. The pusher members generally conform to the forms of the troughs of the chute 47, and each has a downwardly opening slot 112 to accommodate said pusher members to extend along and beyond vertically extending stop members 113. Said stop members 113 extend upwardly of the plate 66 and forms stops for the slugs of cookies as deposited in said chute 47 from the drop chute 45. The stop members 113 have right angled mounting legs 115 adjustably mounted on the plate 66, as by a nut and bolt and slot connection 118 accommodating said stops to be adjustably moved along the chute 47 in accordance with the number of 30 cookies in the slugs, and engage the trailing cookies of the slugs of cookies dropped thereinto upon opening movement of the drop gates 48.

Slug Conveyor

45 The slug conveyor 19 is shown in FIGS. 11, 12 and 13 as being a chain type conveyor including a pair of laterally spaced endless chains 116 of the roller type, the upper runs of which are guided in gibbed guides 117 on rollers 118 of the chain (FIG. 11). The gibbed guides 117 extend along the main frame of the machine and are secured to opposite parallel side frame members 119 thereof, as by angle brackets 120. Said endless chains 116 are shown in FIG. 2 as extending from idler sprockets 121 at the inby end of the conveyor to the drive sprockets 122 at the outby end of the conveyor (FIG. 1). From the drive sprockets 122, the chains extend inwardly and downwardly partially about tension idlers 123. Said tension idlers may be adjustable to take up tension on the chains in a conventional manner. From thence, the conveyor chains extend downwardly about and under idler sprockets 124. The return runs of said endless chains then extend along the lower part of the main frame of the machine to and about idler sprockets 125 adjacent the inby end of the conveyor and angularly upwardly therefrom to the idler sprockets 121.

The drive sprockets 122 are keyed or otherwise secured to a drive shaft 126 extending transversely of the main frame of the machine. The drive shaft 126 is driven from a speed reducer 127 on a pedestal 128 mounted on the main frame of the machine and extending thereabove. The speed reducer 127 is driven from a line shaft 129 through a chain and sprocket drive 129^a and drives the shaft 126 through a chain and sprocket drive 130. The line shaft 129 is in turn driven from the motor 24, which has a motor shaft 131 driving a parallel shaft 132 through a timer belt drive 133. The shaft 132 has a sprocket 135 on its end opposite the timer belt drive, having driving connection with the sprocket 136 through a drive chain 137. The sprocket 136 drives a coaxial sprocket 139 through a safety disconnect drive 140. Said safety disconnect drive 140 is diagrammatically shown in block form in FIG. 25 and may be a ball-type of safety disconnect drive in which balls move out of sockets upon overload conditions, against the bias of springs, in a manner well known to those skilled in the art, so not herein shown or described further. The safety disconnect drive need not necessarily be a ball-type of disconnect drive, but may be of any suitable form, well known to those skilled in the art. The sprocket 139 in turn has drive connection with the line shaft 129 through a chain and sprocket drive 143.

Inside links 144 of the slug conveyor chain 116 have attachments 145 extending horizontally inwardly therefrom, forming supports for drop gate carrier blocks 146, spaced along said chain. Machine screws 147 are provided to secure said drop gate carrier blocks to extend upwardly from the attachments 145 (FIG. 11).

The drop gate carrier blocks 146 are laterally spaced apart by a transverse shaft 148, mounted at their opposite ends on said carrier blocks adjacent the lower end portions thereof and engaged by the slugs of cookies resting on the drop gates 25. The shaft 148 may be pinned or otherwise secured to said drop gate carrier blocks. Spaced above the shaft 148 is a pivot shaft 149 rotatably journaled in said carrier blocks at its opposite ends and forming a mounting for an operating lever 150 having a follower roller 151 on the free end thereof. Said follower roller is engageable with a castellated cam 153 to effect pivotal movement of the lever 150 and opening of the associated drop gate. The lever 150 may be pinned or otherwise secured to the shaft 149. A pair of links 154 is pivoted to an arm 155 of the lever 150 on a transverse pivot pin 156 (FIG. 13). The opposite ends of the links 154 are pivoted to opposite sides of a lever arm 157 extending from a drop gate carrier 159. The drop gate carrier 159 is pivoted to the inside of the drop gate carrier block 146 on a transverse pivot shaft 160. Each drop gate carrier is in the form of a depending lever arm, forming a support for an end of a drop gate 25, which may be secured to the bottom thereof as by machine screws, or any other suitable securing means.

On the opposite side of the conveyor from the follower roller 151 is a drop gate operator 161. Said drop gate operator 161 is of a split construction and is secured to the shaft 149 by a machine screw 162, to be pivoted by the shaft upon pivotal movement of the lever 150. The drop gate operator 161 has a lever arm 163, depending therefrom when the associated drop

gate 25 is in a cookie-supporting position. The lever arm 163 is pivotally connected to an associated drop gate carrier 159 by a pair of links 164 extending along opposite sides of said operator and said drop gate carrier and pivotally connected to said operator and carrier in the same manner the operator lever 150 is connected to its associated drop gate carrier. Stop pins 165 extend inwardly of each drop gate carrier block 146, adjacent the lower end portions thereof and form stops for the drop gate carriers 159 and drop gates 25 in the slug supporting positions thereof (FIG. 11,12 and 13).

The drop gate carriers 159 are biased into engagement with the stops 165 by a torsion spring 166 (FIG. 12) encircling a pin 167 mounted on and extending from a drop gate carrier block 146. One end of the spring 166 engages a pin 169 welded or otherwise secured to a collar on the pin 167 and extending inwardly therefrom. The other end of the spring 166 engages a pin 170 projecting outwardly of the drop gate carrier 159, shown in FIG. 12 as being a right-hand drop gate carrier. The spring 166 thus maintains the drop gate carriers 159 and drop gate 25 in the slug supporting positions in engagement with the stop pins 165 as shown in FIG. 12 and returns the drop gates and carriers in their slug supporting positions, after having been moved to the open position shown in the right-hand side of FIG. 13, by engagement of the follower rollers 151 with the castellated cam 153 (FIG. 5).

Side Guides - Slug Conveyor

The rock shaft 149 forms a mounting for side guides 172 adjustably mounted on said rock shaft for movement toward and from each other in accordance with the number of cookies in the slugs delivered from the transfer conveyor 16, to the slug conveyor 19. As shown in FIGS. 11 and 12, the side guides 172 are mounted on individual carrier members or blocks 173, mounted on the shaft 149 for movement therealong. The mountings for the side guides on said carrier members include machine screws 174 extending through outwardly extending horizontal legs 175 of said side guides and threaded in the top surfaces of said carrier members 173. The side guides flare inwardly of the horizontal legs thereof, to form a hopper-like effect, and guide the slugs of cookies for discharge along said side guides onto the associated drop gates 25.

Each carrier member 173 has a pin 178 extending upwardly therefrom, into a downwardly opening slot extending along a side guide positioner 176. The side guide positioners are adjustably movable toward and from each other at the selection of the operator of the machine, in a manner which will hereinafter more clearly appear as this specification proceeds. The side guides 172 are cut away to accommodate movement of said side guides along the shafts 148 and 149.

Cam Means Operating Slug Conveyor Drop Gates

Referring now in particular to the castellated cam 153 for operating the drop gate carriers 159 and moving the drop gates 25 into slug release positions, a castellated cam 153 is provided for each bagging station. Said cams are operated independently of each other in proper phase relation with respect to travel of the slug conveyor, and dropping of the cookies by operation of the castellated cam 153 into position to

engage the follower rollers 151 and move the drop gates 25 into their slug dropping positions, as shown in FIGS. 5 and 13.

A castellated cam 153 is provided at each bagging station and the mechanism for moving said cams into their operative positions is the same for each station so only one cam and operating mechanism therefor need herein be shown and described. As shown in FIG. 5, the cam 153 is in the form of a cam bar 177 extending longitudinally of the direction of travel of the slug conveyor, and having three lobes 179, where three slugs are to be bagged, and shown as being rectangular in side elevation and spaced apart in accordance with the spacings of the follower rollers 151 on the levers 150. A cam bar having two lobes may be substituted, where two slugs are to be bagged. The cam bar 177 extends along and depends from a carrier bar 180 and may be adjustably secured thereto, as by machine screws or a like securing means. The carrier bar 180 is raised and lowered to bring the lobes 179 into and out of their operative positions by a toggle linkage connection 181.

The toggle linkage connection 181 includes a mounting bar 182 suitably secured to the main frame of the machine and stationary relative to the bar 180 and parallel thereto. The mounting bar 182 forms a mounting for spaced pivot brackets 183. Parallel links 184 are pivoted to and depend from the pivot brackets 183 and form a suspension means for an actuating bar 185, and are pivoted thereto on brackets 186 at opposite ends of said bar. Parallel links 187 are pivoted to the brackets 186 and depend therefrom. Said links are pivoted at their lower ends to mounting brackets 188, mounted on the mounting bar 180, adjacent opposite ends thereof and extending upwardly therefrom.

Restraint of horizontal movement of the cam bar 177 and castellated cam 153 to effect vertical movement of the cam 153, is attained by a restraining link 189, pivoted to a bracket 188 at one end and pivoted at its opposite end to a mounting bracket 190 mounted on the inside of a mounting plate for an actuating cylinder 191. A tension spring 192 connected between the actuating bar 185 and the mounting bar 182, returns the cam 153 into its elevated retracted position free from the rollers 151.

The cylinder 191 is a fluid pressure operated cylinder and may be an air cylinder. A piston (not shown) in said cylinder has a piston rod 193 extending therefrom. A coupler attachment 194 on the end of the piston rod 193 forms a connector for a link 195 on a pivot pin 196. The opposite end of the link 195 is pivoted to the adjacent bar 185, as by a similar pivot pin 196.

The supply of fluid under pressure to the rod end of the cylinder 191 will thus retract the piston rod 193 and vertically move the mounting bar 180 and castellated cam 153 into the operative position shown in FIG. 5, and position the lobes 179 of the cam 153 into position to engage the follower rollers 151 and effect movement of the operating levers 150 in clockwise directions and movement of the drop gate carriers 159 and drop gates 25 in counterclockwise directions, through the linkage connections 154, into the slug release position shown in FIG. 5.

Fluid under pressure may be supplied to the head end of the cylinder 191 through a suitable air valve (not shown) which may be a conventional solenoid operated

valve, the solenoid of which is energized under the control of a limit switch 197 operated by a cam 198 on the cam shaft 104 and rotatably driven thereby. The limit switch 197 is diagrammatically shown in FIG. 23 as having a pivoted switch arm 199, having a follower roller 200 on its free end, suitably biased into engagement with the face of the cam 198 and moving into a notch 202 in said cam to effect closing of the switch and the supply of air to the cylinder 191 each time it is desired to operate the drop gates. The drive to the cam shaft 104 and cam 198 will hereinafter be more clearly described as this specification proceeds. It should here be understood that while the cylinder 191 is described as an air cylinder, it may be a hydraulic cylinder or a solenoid may be substituted for said cylinder.

Adjustment Means for Side Guides

Referring now to FIGS. 11, 12 and 14 to 17, the side guides 172 are adjustably moved toward and from each other by a lateral movement of the side guide positioners 176 slidably supported for movement along the undersides of transverse bars 201. The positioners 176 include a spacer bar 203 and side plates 204 extending along each side of said bar and depend therefrom to form the downwardly opening guide or positioning slot for the pin 178.

The adjustment means for moving the side guide positioners 176 toward and from each other comprise a series of bell cranks 206, pivotally supported on the transverse bars 201. As shown in FIG. 15, the bell cranks 206 are pivoted intermediate their lever arms on vertical pivot pins 207, the vertical axes of which intersect the longitudinal axis of the associated positioning guide 176. The pivot pin 207 is mounted on a support 209 extending perpendicularly of the associated bar 201 and welded or otherwise secured to the top surface thereof. A collar 211 clamped on the vertical pivot pin 207, is shown in FIG. 11 as retaining the bell crank to said pivot pin for pivotal movement about the axis thereof.

The bell crank 206 has a lever arm 212 extending from the pivot pin 207 above and generally in alignment with an associated guide positioner 176. The lever arm 212 has a pivot pin 213 mounted on the end thereof and depending therefrom within a slot 214 in a positioner plate 215 extending along the side guide positioner 176 and suitably secured thereto, to move the guide positioner laterally upon pivotal movement of said bell crank about the axis of the pivot pin 207. The positioner plate 215 has a portion lapping the bar 201 and forming a slidable support for said side guide positioner thereon. The bell crank 206 has a lever arm 217 extending laterally outwardly therefrom and shown in FIG. 15 as extending generally at right angles with respect to the lever arm 212. The lever arm 217 slidably rests upon a support bar 218 extending from the top of the bar 201 perpendicularly thereto. The lever arm 217 has a screw eye 219 mounted thereon and extending upwardly therefrom and secured to the end of said lever arm 217 as by nuts 220 threaded on said screw eye and abutting opposite sides of the lever arm 217. The nuts 220 may accommodate pivotal movement of said screw eye about the axis of the screw.

An adjustment link 221 in the form of a rod extends through the eyes of the screw eyes to simultaneously pivot the bell cranks 206 on one side of the machine upon rectilinear movement of said link. Collars 222 are clamped on said link 221 on opposite sides of the screw eye and have spacers 223 on the insides thereof spacing said collars from said screw eye and abutting said screw eye when actuating the respective bell crank 206. The rods 221 are slidably guided at their outer ends beyond the drive end of the conveyor in vertically extending frame members 224 of the conveyor frame and have knobs 225 on their outer ends, to accommodate the rods or links to be rectilinearly moved by hand and adjustably move the side guide positioners 176 toward and from each other, and position the side guides 172 in accordance with the number of cookies in a slug.

The means retaining the side guide positioners 176 from axial movement along the conveyor is shown in FIG. 11 as being in the form of a series of angles 227 suitably secured to the side plates 204 on their vertical legs and abutting the undersides of the transverse bars 201 along their horizontal legs and extending to one side of said bars in the direction of the positioner plate 215, and extending along one side of said plate.

It will be noted from FIG. 11, that one angle extends inwardly of the right-hand side guide positioner while the aligned opposite angle extends outwardly of the left-hand side guide positioner. The construction of the support means for the side guide positioners otherwise is the same for each side of the slug conveyor.

The portion of the horizontal leg of the angle 227 extending to one side of the transverse bar 201 has a lower strap 228 of a roller chain link 229 secured thereto, as by machine screws 230. The straps of the chain link extend along the tops and bottom of two spaced bars 231 connected together at their opposite ends by end connectors 232. The rollers of the chain link extend between and engage the inner sides of the spaced bars 231 and guide the angle 227 and hold said angle and the side guide positioners 176 from axial movement relative to the main frame of the machine. The inner bar of the spaced bars 231 is suitably secured to the cross frame member 201 to extend to one side thereof, as shown in FIG. 15.

Secured to the top surface of the horizontal leg of the angle 227 and extending partially along the spaced bars 231 is an inverted L-shaped member 233 abutting the top surface of the horizontal leg of said angle 227 along one leg and positioning its horizontal leg to extend over the roller chain link 229, and form a mounting for mounting brackets 235 for an off-center toggle clamp 236.

The toggle clamp 236 may be of a conventional form operated by a hand lever 244 and having a clamping arm 245 pivoted to the bracket 235 at one end and having a pair of toggle links 247 pivoted thereto at the points of connection of said links together. One toggle link extends upwardly of the pivot to the clamping arm 245 and is shown as being pivoted to the lever 244, while the opposite toggle link depends from the pivot and is pivoted to the bracket 235 coaxial with the pivot of the lever. The clamping arm 245 extends over the transverse bar 201 and has a machine screw 248 threaded therein and extending therethrough. The lower end of the machine screw 248 has a pressure pad

249 thereon, moved into clamping engagement with a bar 201 as the toggle lever 244 is in its upright position shown in FIG. 17. The clamping pad 249 is released to accommodate free lateral adjustable movement of the side guide positioners as the lever 244 is turned in a counter-clockwise direction to break the over-center relation of the links of the toggle linkage connection.

The two side guide positioners may thus be laterally adjusted by movement of the links 221 effected by 10 operation of the hand knobs 225 to position the side guides 176 in the proper spacing to accommodate a slug of cookies to be dropped therebetween and to hold the slug of cookies in an upright position on the respective drop gate 25 during travel of the slug conveyor from its inby to its outby end.

Bagging Station Selectors and Cam Drive Mechanism

FIGS. 18 to 25 inclusive illustrate the drives to the 20 various operative cams and cranks at each bagging station for varying the speeds of the cams and cranks and the phases of operation thereof, in accordance with the number of bagging stations in operation, and the number of slugs delivered to each bagging station during each cycle of operation of the bagging station drop gate 48 and pusher 73. FIG. 18 shows the line shaft 129 in transverse section and shows parallel jack shafts 250 disposed above said line shaft. Each jack shaft is provided to drive the drop gate and pusher operating mechanism at each side of the main frame. The line shaft 129 has a spur gear 251 mounted thereon and keyed or otherwise secured thereto, to be driven therefrom. The spur gear 251 meshes with a change speed gear 252 mounted on a shaft 253 and removably keyed or otherwise secured thereto. The shaft 253 is journaled in a bearing bracket 255 mounted on an arm 256. The arm 256 in turn is mounted for adjustable movement about the axis of a jack shaft 250. The arm 256 has a slot 257 extending partially thereacross and struck from an arc, the center of which arc is the axis of the jack shaft 250, on which said arm is mounted. A bolt 259 is carried in a cross frame member 260 and extends through the slot 257 to retain the arm 256 in position when the proper change speed gear 252 is in mesh with the gear 251.

The lower end portion of the arm 256 has a recessed portion 261 extending therealong forming a slidable guide for an extensible end portion 262 of said arm 256. The extensible end portion 262 is provided with a pair of slots 263 through which extend bolts 264, which may have nuts (not shown), threaded on the ends thereof, to positively hold the extensible end portion 262 to the arm 256 and maintain the required spacing between the shaft 250 and shaft 253 to maintain the proper tension on a drive chain 265 meshing with a sprocket (not shown) keyed on the opposite end portion of the shaft 253 from the change speed gear 252. The chain 265 drives the jack shaft 250 through a sprocket 267 keyed or otherwise secured to said jack shaft.

The change speed gear 252 is preferably keyed to the shaft 253 and is retained to said shaft by a bolt 269 threaded in said shaft and abutting a washer disposed between the head of the bolt and said change speed gear. The change speed gear 252 may be removed and replaced with a change speed gear of either a greater or

a smaller number of teeth in accordance with the desired speed of operation of the jack shafts 250. The chart in FIG. 25 gives the number of teeth in the gear 252 when driven by a 24 tooth pinion for bagging two or three slugs to a bag, by the use of from two to six bagging stations and shows that as the number of slugs to a bag and the bagging stations in use increase, it being understood that the speed of each jack shaft is 8/3 revolutions per slug cycle regardless of the number of stations or the number of slugs loaded. The line shaft 129 is driven at a fixed speed of 2 revolutions per slug in the slug conveyor 19.

It should here be understood that a slug cycle is the number of slugs dropped out of the slug conveyor during one complete operation of all of the bagging stations used. In a twelve slug cycle where four stations are used, twelve consecutive slugs will pass the four stations used, all of the slugs being dropped out of the slug conveyor in the proper sequence in groups of three. The jack shaft 250 makes 8/3 revolutions per cycle for any condition of stations and slugs per bag.

The jack shafts 250 are connected to rotate together in opposite directions at the same rates of speeds through meshing spur gears 270. The right-hand jack shaft 250 in FIG. 18 serves as a drive shaft for bagging stations two, four and six, while the left-hand jack shaft 250 serves as a drive shaft for bagging stations one, three and five.

Each jack shaft 250 has three sprockets 271 spaced therealong and keyed or otherwise secured thereto, one sprocket being provided for each bagging station.

Phase Selector Drive from Jack Shaft to Cam Shaft

A separate cam shaft 104 and a phase selector drive 273 is provided for driving the associated cam shaft, from its jack shaft at bagging stations one to six. The phase selector drives at each bagging station are the same so only one phase selector drive need herein be shown and described. The cam shaft 104 extends in the direction of travel of the slug conveyor and is journalled on frame members 274 forming a part of the main frame of the machine, in bearing boxes 275 mounted on and extending upwardly of said frame members. The crank 103 for driving the slug pusher 73 back and forth is keyed or otherwise secured to one end of said crank shaft in spaced relation with respect to the adjacent bearing box 275.

A drag brake 276 is disposed between the crank 103 and its adjacent bearing box 275. As shown in FIGS. 19 and 20, a bracket plate 277 is secured to the outer side of the frame members 274 as by machine screws, and extends upwardly therefrom and forms a mounting adjacent its upper end for a bolt 279. The bolt 279 extends through a boss 280 extending radially of the periphery of the drag brake and forms a pivotal mounting for said drag brake. The drag brake is in the general form of a split collar having a split portion 281 having lugs 282 extending outwardly of the periphery of said drag brake, the facing sides of which define the split portion 281 of said drag brake. A machine screw is threaded in the lower lug 282 and extends loosely through the upper lug. A spring 283 biases the lugs 282 toward each other to maintain a drag on the cam shaft 104 and prevent overrunning thereof in a conventional manner.

The drive to the cam shaft includes an overrunning clutch of a conventional form including a driven member 287 keyed or otherwise secured to the shaft 104 and a driving member 288 for driving said driven member through the usual overrunning clutch jaws. Said driving member 288 is journalled on the shaft 104 on a bearing 289 and abuts a drive sprocket 290 at its end opposite the driven member and is secured to said sprocket as by machine screws 291 to be driven therefrom. The sprocket 290 is meshed with and driven from an endless chain 293 driven from a sprocket 271 on the jack shaft 250.

Journalled on the cam shaft 104 adjacent the sprocket 290 and at the opposite side thereof from the overrunning clutch, is a disk 295 having a generally cylindrical periphery, and forming an adjustment means for the cam shaft 104 and crank 103 and cams 63 and 197 on said cam shaft. The disk 295 has a partial annular ring 296 spaced to one side thereof, and extending about the sprocket 290, and shown in FIG. 20 as being formed integrally with said disk 295. The disk 295 also forms a mounting for parallel shafts 297 extending parallel to the cam shaft 104 and having idler sprockets 298 freely journalled thereon. The idler sprockets 298 extend within an open portion 299 of said partial ring 296 and are in direct alignment with the sprocket 290.

The drive chain 293 is trained about its sprocket 271 under a tension idler 300 along the outer periphery of the partial ring 296 about one idler sprocket 298 inwardly therefrom about the drive sprocket 290 and outwardly of said drive sprocket about the other idler sprocket 298. From the outgoing idler sprocket 298, the chain 293 is trained about the periphery of the partial ring back to the drive sprocket 271. The partial ring 296 has a diameter equivalent to a sprocket having twice the pitch diameter or number of teeth of the sprocket 290. During the drive to the cam shaft 104, the disk 295 is held from rotation, and the sprocket 290 is driven from the sprocket 271 and chain 293 in the manner just described.

The disk 295 forms an angular adjustment means for adjusting the phase of the cam shaft 104 and cams and crank thereon, and is adjustably moved about the axis of the cam shaft 104 by rotation of a threaded shaft 301, threaded in a block 302 trunnioned to one side of said disk on trunnion bearings 303 (FIGS. 20 and 21). One trunnion bearing is carried in said disk and the other is carried in an arm 304 of a bracket member 317 secured to and extending along said disk and spacing the arm 304 in parallel relation with respect to the face of said disk.

The disk 295 has a hub 306 extending outwardly therefrom in an opposite direction from the partial ring 296, and abutting a shoulder portion 307 of a shouldered sleeve 309. A bearing 310 forms a bearing for said hub on the reduced diameter portion of said shouldered sleeve. A thrust bearing 311 engages the inside of the shouldered sleeve 309, the bearing 310 and disk 295 and is spaced from the sprocket 290 as by a spacer 312. The shouldered sleeve 309 is spaced radially from the shaft 104 and is mounted on a bracket plate 313 extending inwardly of a side frame member 274. A cap screw 315 is provided to retain said shouldered sleeve to said bracket plate to form a bearing support for the disk 295.

The angular timing position of the cam shaft 104 with respect to the slug conveyor 19 and the cam 63, crank 103 and cam 198 may be changed during operation of the machine, to synchronize dropping of the slugs, with the speed of travel of the slug conveyor. A hand crank 316 on the outer end of the threaded adjustment shaft 301 is turned by hand to rotate the disk 295 about its axis, by threaded engagement of said shaft 301 with the block 302. The chain 293 being meshed with its drive sprocket is locked by said drive sprocket 271 and jack shaft 250. As the disk 295 is turned by rotation of the hand crank 316, the idler sprockets 298, turned by said disk, the pinions 298 will be bodily moved about the axis of the cam shaft 104 and will walk about said chain in the manner of planetary pinions walking about the internal gear of a planetary geared reduction device. This will take up tension on the slack side of the chain and place slack on the normally tight side of the chain. This will turn the sprocket 290 and cam shaft 104 at an angle of travel stepped up three times with respect to the angle of travel of the disk 295.

As for example, the travel of the nut or block 302 of 1 inch attained by rotation of the hand crank 316 and threaded shaft 301 will turn the disk 295 through an angle of $13\frac{1}{2}^\circ$ and will adjustably move the cam shaft 104 through an angle of 40° .

The threads on the threaded shaft 301 and block 302 are of such a pitch, that one complete turn of the hand crank 316 and threaded shaft 301 will equal 5° of cam shaft adjustment, and 9 inches of travel of the threaded block or nut 302 will equal 120° of travel of the disk 295 and 360° of travel of the cam shaft 104.

A stop 318 is mounted on a housing 319 for the threaded shaft 301 and engages the nut 302 to limit adjustable movement of the disk 295 to a zero position of adjustment in one direction. A stop 329 on the opposite end of the housing 319 engages the nut 302 upon rotation of the disk 295 for 120° , and determining an opposite neutral position of the cam shaft 104.

A portion of the periphery of the disk 295 may be calibrated in degrees from 0° to 360° and subtends an angle on the periphery of the disk 295 of 120° . An indicator arrow 321 is positioned by a rod 322 to extend over the portion of the disk which is calibrated, and indicate the position of said disk as adjusted by the hand wheel 316. The rod 322 in turn is mounted on and extends from a block 323 adjustably mounted on a vertical rod 324, mounted on the bracket plate 313, and extending upwardly therefrom (FIG. 21).

The overrunning clutch 285 at each bagging station is used to manually disconnect the station when not in use. As shown in FIGS. 19 and 20 and as diagrammatically shown in FIG. 22, the driven member 287 has an outwardly opening slot 325 extending thereabout having a clutch dog 327 pivoted within said slot on a pivot pin 329, journaled in said driven member to pivot with said dog. The pivot pin 329 has an extension 330 extending within the driving member 288 and forming a driving dog for the overrunning clutch. The driving dog is adapted to be engaged by a driving dog 331 in the driving member 288. The dogs 330 and 331 having facing circumferential surfaces 332 and 333 which clear each other and accommodate the driving member to freely rotate relative to the driven member, when the dog 327 is in the position shown in FIGS. 20 and 22. A

suitable spring (not shown) may be provided to provide a driving connection between the dogs 330 and 331 and to bias said dogs to engage each other and thereby engage the clutch. The dog 327 is held in position to disconnect the drive to the shaft 104 by a bell crank 334, pivoted intermediate its ends on a pivot pin 335 mounted on a bracket 336 extending inwardly of the top surface of a side frame member 274.

The bell crank 334 has a lever arm 337 engaging the end of the dog 327 to disconnect the drive to the cam shaft 104 and has an opposite depending lever arm 338 having a link 339 pivotally connected thereto and extending outwardly therefrom through a bracket member 340. A pull handle 341 is mounted on the outer end of the rod 339 and is effective to release the arm 331 of the bell crank from the dog 327 and to thereby release said dog 327 to pivot outwardly and effect a driving connection between the clutch dogs 330 and 331, in a manner well known to those skilled in the art so not herein shown or described further. A latching lever 343 is pivotally mounted on the racket 340 intermediate its ends and is biased by a spring 344 to engage a shouldered end 345 of the pull handle 341 and hold the bell crank 334 in position to effect disengagement of the 1 revolution clutch, and thereby disconnect an associated bagging station, when it is desired to take a particular bagging station out of service.

It should here be understood that as long as the dog 327 is free, and the bell crank 334 is out of engagement with said dog, the shaft 104 will rotate until it is moved into position to engage said dog. The bell crank being pivoted about a fixed axis relative to the dog will always stop rotation of the cam shaft 104 in the same position and said cam shaft will always start to rotate from the same position upon release of the dog, to thereby prevent the shaft 104 from getting out of phase.

The cam 198 is mounted on and extends radially of a plate 346 extending radially of a hub 347, keyed or otherwise secured to the cam shaft 104 and rotatably driven thereby. A machine screw 349 is provided to detachably mount the cam 198 to the plate 346. An interengaging connection (not shown) may also be provided between said plate and cam to assure positive rotation of said cam with the plate 346 and to properly position said cam relative to said plate. A different cam 198 is provided for each change in stations in operation and change in the number of slugs delivered at each station to assure a continuous flow of slugs to the drop chutes 45 and bagging troughs 47.

It should be understood that while cookies and bagging stations are referred to herein, that the apparatus may be used for loading and packaging a wide variety of articles which are supplied in groups or slugs, and that the bagging stations may be various types of packaging stations in which the groups of slugs may be supplied for packaging my mechanized packing machines.

We claim as our invention:

1. In an apparatus for supplying slugs of articles, such as cookies in preselected side-by-side groups, and in combination with a transfer conveyor, conveying counted slugs in side-by-side and end-to-end relation, and releasing means for said counting conveyor, releasing side-by-side slugs therefrom,

a slug conveyor disposed beneath said transfer conveyor having a material carrying run in slug receiving relation with respect to said transfer conveyor and traveling at a uniform rate of speed at right angles with respect to the direction of travel of said transfer conveyor, 5
 slug conveyor drop gates forming flights for said slug conveyor, means operating said drop gates to discharge a 10 preselected number of slugs therefrom, a series of bagging stations spaced along said slug conveyor, each including a drop chute in slug receiving relation with respect to said slug conveyor, divided in accordance with the number of slugs to be dropped thereto, drop chute drop gates forming the bottom of said drop chute, 15 each supporting a slug dropped thereto, means operable to move said drop gates to release the slugs therefrom, loading means disposed beneath said drop chute in slug receiving relation with respect thereto, means operating said loading means in timed relation 20 with respect to operation of said drop gates, individual operating and control means at each bagging station, operating said means for operating said drop gates of said slug conveyor, said means for operating said drop gates of said drop chute, and said loading means in timed relation 25 with respect to each other, means selectively operable to render any one of said operating means and bagging station inoperative, and other means synchronizing the phase of operation 30 of said drop gates of said slug conveyor, and said drop gates of said drop chute and said loading means in accordance with the number of slugs being loaded and the number of stations in operation. 35

2. The apparatus of claim 1,
 wherein the loading stations are disposed along each side of the slug conveyor, wherein a line shaft is provided for driving the means 45 for operating the slug conveyor drop gates, the drop chute drop gates and the loading means, and wherein the drive means from said line shaft includes an individual phase selector drive at each bagging station, operable to change the phase of operation 50 of the slug conveyor drop gates drop chute drop gates and the loading means in accordance with the number of stations in operation and in accordance with the number of slugs delivered at each loading station. 55

3. The apparatus of claim 2,
 wherein manually operable means are provided to disconnect a preselected phase selector drive from an associated bagging station, and include, a stop member selectively positionable to stop 60 rotation of the drive at a preselected position in the cycle of rotation thereof.

4. The apparatus of claim 2,
 wherein the drive means also includes an overrunning clutch at each station, wherein the stop is positionable to disengage said 65 overrunning clutch at a preselected point in the

cycle of rotation of said clutch and to release said clutch and assure the operation of said clutch at the same point in the phase of rotation of said drive means as the point of stopping of rotation thereof.

5. The apparatus of claim 2,
 wherein the phase selector includes a single drive shaft, effecting operation of said slug conveyor drop gates, said drop chute drop gates and said loading means, wherein the drive to said drive shaft includes an overrunning clutch, and wherein the stop is operable to disengage said clutch to take a selected station out of operation by disconnecting the drive to said drive shaft.

6. The apparatus of claim 5,
 wherein the drive from the line shaft includes at least one jack shaft, wherein means are provided to change the speeds of the jack shaft as the number of slugs being loaded and stations in operation changes, and wherein the phase selector includes means selectively operable to change the angular relation of said drive shaft relative to the means for operating the slug conveyor drop gates, the drop chute drop gates and the loading means relative to the number of stations in operation, to assure operation of said slug conveyor drop gates, said drop chute drop gates and said loading means at the required phase relation with respect to the number of stations in operation, the number of slugs being loaded and the changes in speed of said jack shaft.

7. The apparatus of claim 6,
 wherein the phase selector is a planetary-type of phase selector and includes a disk coaxial with said drive shaft, a pair of spaced idlers freely journaled on said disk for rotation about axes spaced radially from and parallel to the axis of rotation of said drive shaft, means for holding said disk from rotation, a driven member coaxial with the center of said disk, means driven from said jack shaft for driving said idlers and driven member, and means for changing the angular position of said disk while said jack shaft is in operation, said idlers reacting against said drive by said jack shaft and effecting the angular positioning of said driven member by bodily movement of said idlers and rotatable movement of said idlers, reacting against said drive, and thereby changing the angular position of said drive shaft relative to said disk.

8. The apparatus of claim 7,
 wherein the drive connection from said disk to said driven member to adjustably move said drive shaft relative to said disk, is a stepup drive connection.

9. The apparatus of claim 8, including
 a hand wheel and screw rotated thereby are provided for angularly moving said disk to change the phase of operation of said drive shaft, and a nut threaded on said screw, and pivoted to said disk for movement about an axis intersecting the axis of turning movement of said screw, and perpendicular thereto.

10. The apparatus of claim 8, including

- a sprocket on said jack shaft,
an endless chain driven from said sprocket and
trained about one idler and inwardly therefrom to
and about said driven member and from said
driven member outwardly about the second idler 5
and back to said jack shaft.
11. The apparatus of claim 10,
wherein a semi-annular ring is spaced from and at-
tached to said disk and extends about said drive
shaft coaxially therewith, and has an opening 10
therein within which said idlers extend, and
wherein the periphery of said ring forms a guide
means for the incoming and outgoing runs of said
endless chain.
12. The apparatus of claim 5, including means main-
taining the revolutions of the jack shaft per slug cycle 15
the same regardless of the number of slugs being loaded
and number of stations in operation,
wherein the drive shaft is a cam shaft,
wherein the phase selector drives said cam shaft one 20
revolution per slug discharge cycle,
wherein a first cam is driven by said cam shaft for
operating the means for operating said slug con-
veyor drop gates,
a second cam is mounted on said cam shaft for 25
operating means for operating said drop chute
drop gates and moving said drop gates into position
to release slugs of cookies discharged
therein by said slug conveyor drop gates,
and a drive member is mounted on said shaft for 30
operating said loading means to move into loading
and return positions during one revolution of
said cam shaft, and
wherein the phase selector for driving said cam shaft 35
from an associated jack shaft is operable to vary
the position of said cam shaft and cams and
synchronize the phases of operation of said cam
and said drive member to effect a completion of
the drop gate opening and closing operations and 40
the loading operation and return of the drop gates
and loading means in the proper phase relation
with respect to each other and speed of travel of
said jack shaft and slug conveyor.
13. The apparatus of claim 12, 45
wherein the phase selector is a planetary-type of
phase selector and includes a disk coaxial with said
drive shaft,
a pair of spaced idlers freely journaled on said 50
disk for rotation about axes spaced radially from
and parallel to the axis of rotation of said drive
shaft,
means holding said disk from rotation,
a driven member coaxial with the center of said 55
disk,
means driven from said jack shaft for driving said
idlers and driven member upon holding said disk
from rotation, and
means for changing the angular position of said 60
disk while said jack shaft is in operation,
said idlers reacting against said means driven from
said jack shaft upon bodily movement thereof
about said cam shaft and rotatably driven
thereby to effect a drive to said driven member,
and change in the angular position of said drive 65
shaft relative to said disk.
14. The apparatus of claim 13, including

- a hand wheel and a screw rotated thereby, for rotat-
ing said disk to change the phase of operation of
said drive shaft,
a nut threaded on said screw,
and means pivotally connecting said nut to said disk,
for movement about an axis intersecting the axis of
turning movement of said screw and perpendicular
thereto, and spaced radially from the axis of rota-
tion of said cam shaft.
15. The apparatus of claim 12,
wherein a sprocket is secured to said jack shaft and
rotated therewith,
wherein the means driven from the jack shaft for
driving said idlers and driven member comprises
an endless chain meshing with said sprocket and
trained about said idlers and driven member and
having driving engagement therewith.
16. The apparatus of claim 15, including
a semi-annular ring spaced from and attached to said
disk and extending about said cam shaft, coaxially
therewith and having an outside diameter propor-
tionate to the number of teeth in said sprocket,
an opening through the periphery of said ring on op-
posite sides of said idlers,
the periphery of said ring forming a guide means for
said endless chain, guiding said chain to and from
said idlers and accommodating said chain to be
trained about said drive sprocket on said cam
shaft.
17. The apparatus of claim 16, including
a tension idler maintaining tension on said endless
chain,
whereby rotation of said disk to vary the change in
phase of operation of said cam shaft effects the
tensioning of the slack side of the chain against
said tension idler, to accommodate rotation of said
driven member and cam shaft and the placing of
slack on the normally tight side of the chain upon
holding said jack shaft from rotation.
18. The apparatus of claim 17,
wherein the cam on said drive shaft for operating
said slug conveyor drop gates is detachably
mounted on said shaft, to accommodate the
dropping of said slugs by said slug conveyor drop
gates in accordance with the number of stations in
operation, and the required number of slugs to be
discharged at each bagging station, by the in-
terchanging of selected cams, to maintain a
uniform discharge of slugs and a continuous load-
ing operation thereof.
19. The apparatus of claim 18,
wherein a cam is provided at each bagging station
having lobes spaced in accordance with the
number of slugs being loaded,
wherein said cam is mounted for movement toward
said slug conveyor into an operative drop gate
release position, and away from said slug conveyor
to accommodate closing of said drop gates into
position to support slugs of cookies deposited
thereon,
wherein the means moving said cam toward and from
said slug conveyor is operated by said first cam on
said jack shaft in preselected time relation with
respect to opening of said drop chute drop gates,
to accommodate the depositing of slugs of cookies

- therein when said slug conveyor drop gates are in their closed positions.
20. The apparatus of claim 19, wherein a rectilinearly movable motor is provided to move said last-mentioned cam toward and from said slug conveyor, and wherein a limit switch operated by said first cam is provided to effect operation of said rectilinearly movable motor.
21. The apparatus of claim 20, wherein the rectilinearly movable motor is a fluid pressure operated motor, and wherein the limit switch effects the supply of fluid under pressure to and the release of fluid under pressure from said motor.
22. The apparatus of claim 19, including an actuating arm for each flight of said slug conveyor, pivotally mounted on said slug conveyor, an operative connection between each actuating arm and slug conveyor drop gate, means biasing said actuating arm and drop gate in a cookie supporting position, and a follower roller on said actuating arm engageable with a lobe of said cam to move said arm and the drop gate associated therewith into a slug release position.
23. The apparatus of claim 22, including a fluid pressure operated cylinder for moving the cam at a bagging station toward and from said slug conveyor, a limit switch operated by said first cam on said cam shaft and effective to supply fluid under pressure to said cylinder to move said cam at said bagging station into operative association with said follower rollers on said actuating arms.

24. The apparatus of claim 23, including spring means biasing said cam at said bagging station out of operative association with said follower rollers, and other spring means biasing said drop gates into their cookie supporting positions and said actuating arms and follower rollers in position to engage said cam at said bagging station upon movement of said cam toward said slug conveyor during each cycle of rotation of said cam shaft.
25. The apparatus of claim 24, wherein the loading means at each bagging station comprises a pusher at each station, pushing slugs of cookies in laterally aligned relation with respect to each other for loading, wherein the means operating said pusher comprises a crank secured to said cam shaft, and a link and lever connection between said crank and pusher operating said pusher in a slug loading direction for a portion of a revolution of said crank and returning said pusher for the balance of the cycle of rotation of said crank.
26. The apparatus of claim 25, including a cam groove in said second cam, a lever pivoted for movement about an axis parallel to the axis of rotation of said cam shaft, a follower roller on said lever engaging said cam groove, and a link and lever connection between said lever and said drop chute drop gates opening said drop chute drop gates during a portion of the cycle of rotation of said cam, and closing of said drop gates and holding of said drop gates closed during opening of said slug conveyor drop gates, for discharging slugs of cookies therein.
